UNITED STATES PATENT OFFICE.

CHRISTOPHER J. ROACH, OF MIDDLETOWN, CONNECTICUT.

CHAIN CONSTRUCTION.

1,257,398.

Specification of Letters Patent. Patented Feb. 26, 1918.

Application filed October 8, 1915. Serial No. 54,720.

To all whom it may concern:

Be it known that I, CHRISTOPHER J. ROACH, a citizen of the United States, residing at Middletown, in the county of Middlesex and State of Connecticut, have invented certain new and useful Improvements in Chain Constructions, of which the following is a specification.

My invention relates to improvements in chain construction, and the object of my improvement is simplicity and economy in construction and convenience and efficiency in use.

In the accompanying drawing:—

15 Figure 1 is a side elevation of a portion of a chain made in accordance with my improved construction.

Fig. 2 is a similar view, on an enlarged scale, of a pair of adjacent links.

20 Fig. 3 is a plan view of a blank for one of the links.

Fig. 4 is a view corresponding to Fig. 2 of a pair of links for a larger size of chain.

Fig. 5 is a plan view of a blank for one 25 of the links shown in Fig. 4.

Fig. 6 is a side elevation of the same.

My improved chain construction comprises the use of a series of similar U-shaped links that are hooked together to make up the desired length, and which links involve special features of construction, to be described.

The blank for the links shown in Fig. 1, which blank is shown in Fig. 3, comprises a forged piece of bar form, having the middle portion 10 of appreciable length and of cross-section corresponding to that of the original bar, and having end portions 11 that are similar and each being flattened out and provided with an opening 12 to form an eye.

40 The inclosing walls for the opening or eye 12 comprise the side bars 13 at the sides and the end bar 14 cross-connecting the ends thereof. The opening 12 is so positioned that extra thickness is provided for the end bar 14, relatively to the side bars 13, so as to provide for wear, as in use the inner edge portion of the bar 14 serves as a bearing surface.

50 The blank, as shown and described, is bent into U-shape to form the finished link, being bent symmetrically along the middle portion 10, the flattened end portions 11, with the eyes 12, being brought to oppose one another and in parallelism and in spaced relation. The space 15 between the opposed

end portions 11 is made to correspond to the thickness of the side bars 13 of the eyes 12 of the mating link, so that as the pair of opposed eyes 12 of the said mating link are 60 slipped over one of the eyes 12, corresponding to the flattened end portion 11, in threading the links together, the two side bars 13 on one side of the said eyes 12 will freely pass along the space 15, the two links being positioned at an angle of substantially 65 ninety degrees during such threading.

By having the eyes in spaced relation as described the assembling and dismantling of the chain is facilitated and the same may 70 be effected without the necessity of forcing apart or springing the arms of the U-shaped links.

In order to insure the spaced relation of the end portions 11 as described I find it desirable to provide individual seats for each of the crossbars 14, the said seats 16 being in proper spaced relation, and separated by some form of division wall, such as the hump 17 formed by a kink or inward bend of the 80 material of the bar of which the link is formed, and positioned at the apex portion of the link.

In the case of the larger sizes, shown in Figs. 4, 5, and 6, the construction is generally the same as that described, the exception being in the manner of forming the hump 17^a, which is in the form of a forging, as distinguished from a bend, and may consist of a diminutive rib as shown or any 90 other form of projection.

It will be noted that the humps 17 and 17^a serve also to bring the flattened end portions 11 substantially in line when the chain is under strain, the same of course being arranged in pairs.

In my improved form of chain construction as described the full strength of the bar is available for tensile strain and excess material is provided at the eyes to allow for 100 wear.

My chain construction as described is adapted for producing chains of large material for heavy duty and at the same time to permit of readily assembling and disassembling the links at will, and without the use of special tools or any tools whatsoever, such assembling and disassembling being permissible and positively provided for. These results are possible by reason of the combination of features, as shown and described, comprising the bar-like form for the blank,

as distinguished from wire, the loop being formed of the original bar by bending into substantially circular form, the eye portion being duplex, being composed of a pair of opposed eyes, the walls of the individual eyes being flattened, the openings of the eyes being of such size as to slip over the flattened walls of one of the mating eyes, the inter-engaging of the links in the manner described being facilitated by having the opposed eyes in spaced relation, and finally such spaced relation being made positive and permanent by providing individual seats for the individual eyes on the loop with which they are engaged by means of the division wall or separator in the form of a projection on the inner face of the loop.

Heretofore, in chains for heavy duty no provision has been made for assembling and disassembling the links in the manner described.

I claim as my invention:—

In chain construction for heavy duty

chains, a series of similar links adapted to be assembled and disassembled without the use of tools or auxiliary devices, the said links being formed of relatively heavy bar material and comprising a body portion of loop form and end portions in opposition and having eyes that are adapted to slip over the individual eyes of a mating link, the said body portion having on the inner wall a projection-separator for providing individual seats for the eyes of the mating link, the link structure being set so that the opposed eyes are spaced suitably to provide a sliding fit for the side wall portions of the eyes of the mating link, and the eye structure being appreciably flattened so as to require a minimum of such spacing of the opposed eyes.

CHRISTOPHER J. ROACH.
